Specification for Design.

Patented Dec. 27, 1921.

Application filed September 27, 1920. Serial No. 413,176. Term of patent 14 years.

To all whom it may concern:

Be it known that we, JAMES F. QUIMBY and MARION O. QUIMBY, both citizens of the United States, and both residents of Pawtucket, in the county of Providence and State of Rhode Island, have invented a new, original, and ornamental Design for a Brush, of which the following is a specification, reference being had to the accompanying drawing, forming part thereof.

In this drawing, the figure is a perspective view of the brush.

We claim:

The ornamental design for a brush, as shown.

In testimony whereof, we affix our signatures in the presence of two witnesses.

JAMES F. QUIMBY.
MARION O. QUIMBY.
